UNITED STATES PATENT OFFICE.

HANS BAERBALCK, OF CINCINNATI, OHIO, ASSIGNOR TO THE AMERICAN TOOL WORKS COMPANY, OF CINCINNATI, OHIO, A CORPORATION OF OHIO.

METAL-WORKING MACHINERY.

Application filed December 20, 1926. Serial No. 155,964.

My invention relates to indicating means for indicating the adjustments of travel of a reciprocating member, and to means for maintaining the adjusted parts in adjusted relations.

I have exemplified my invention as applied to a metal shaping machine employing a reciprocating ram and a rocker-arm for reciprocating the ram, the motive agency for the rocker-arm being a crank-pin adjustable with relation to its axis of rotation for qualifying the length of stroke of the ram, the indicating means being employed to indicate the adjustments of the crank-pin; further means being employed to maintain the parts in adjusted relations.

It is the object of my invention to provide novel means arranged for operating in novel manner whereby the adjustments of the crank-pin are indicated in convenient position for the operator, so that the adjustments made may be readily read by the operator while making the adjustments; and, further, to provide novel means for holding the parts in adjusted relations.

The invention will be further readily understood from the following description and claims, and from the drawings, in which latter:

Fig. 1 is a vertical axial section of my improved device, taken in the plane of the line 1—1 of Fig. 3, and partly broken away.

Fig. 2 is a plan view showing a detail of the same.

Fig. 3 is a side elevation, partly in section, taken in the plane of the line 3—3 of Fig. 1, partly broken away.

Fig. 4 is a cross-section of my improved device, taken in the plane of the line 4—4 of Fig. 1.

Fig. 5 is a cross-section of the same, taken in the plane of the line 5—5 of Fig. 1.

Fig. 6 is a cross-section of the same, taken in the plane of the irregular line 6—6 of Fig. 1.

Fig. 7 is an enlarged axial section, similar to Fig. 1, partly broken away; and.

Fig. 8 is a perspective view of the handle, partly broken away.

The shaping machine exemplified comprises a usual frame 11, on which there is an upper guideway 12. A tool-ram 13 is reciprocated lengthwise in the guideway, and is arranged to carry a usual tool-holder 55 at its end for receiving the tools. The ram

is reciprocated by a usual rocker-arm 14, pivoted at its lower end on a shaft 15, supported in bearings 16 in the frame. The upper end of the rocker-arm is articulated at 17 with a link 18, which latter is articulated at 19 with a nut-block 20.

The nut-block is adjustable lengthwise of the ram by means of a screw-rod 25, threaded in the nut-block, and journaled and held endwise in usual manner in the ram, the nut-block being clamped in adjusted positions to the ram by means of a handle 26, in usual manner, for positioning the path of stroke of the tool-ram.

The rocker-arm is provided with a usual longitudinal guideway 29, in which there is a slide-block 30, which forms a bearing for the crank-pin 31 journaled therein. The crank-pin is on a bull-wheel 32, suitably rotated at selective speeds, as by having a suitable drive pinion driven at selective speeds meshing with the gear-teeth 33 thereon.

The stroke of the tool, that is, the distance which the tool moves at each reciprocation of the rocker-arm 14, is governed by the position of the crank-pin 31 with relation to the axis of rotation of the bull-wheel. The adjustment of the crank-pin is effected by mounting the crank-pin on a slide-block 35, which is adjustable lengthwise in a dovetailed guideway 36 in the bull-wheel. The block 35 has a threaded bearing 37, an adjusting screw 38 being threaded therethrough.

The adjusting screw is journaled and held endwise in a bearing 39 on the bull-wheel, and is rotated by a bevel pinion 40 fixed thereon, with which a bevel pinion 41 meshes. The bevel pinion 41 is fixed on an adjusting shaft 42.

The hub 45 of the bull-wheel has a bushing 46 therein, which is fixed to the bull-wheel by a screw 47, so as to rotate with the bull-wheel. A block 48 is fixed to this bushing, as by a positioning screw 50, between a hub 51 of the block and the bushing.

The hub of the bull-wheel is rotatable in a bearing 54 of the frame of the machine, in which a bushing 55 is located.

A bearing-sleeve 56 is fixed to the bearing 54 by screws 57, the bearing-sleeve having an annular flange 58 through which the screws are received. The flange spans the outer end of the hub of the bull-wheel, and the

bearing-sleeve forms a bearing for the outer end of the bushing 46 fixed to the bull-wheel. The bull-wheel is held endwise in the bearing 54.

5 A housing 61 comprises an inner section 62 and an outer section 63 connected by screws 64. It has a bearing 65 about the bearing-sleeve 56 and a sleeve extension 66, which latter forms a housing for the indicating means.

A shell 69 has a flange 70, by means of which it is secured, as by bolts 71, to the block 48, so as to rotate with the bull-wheel.

A bushing 72 is received about a hub 73 on the block 48 about the shaft 42, and is located endwise between the block 48 and an inner annular shoulder 74 on the shell 69. The shell is positioned concentrically about the axis of the adjusting shaft 42, and the 20 adjusting shaft is held endwise with relation to the bevel-pinions 40, 41.

A collar 75 is connected with the adjusting shaft so as to rotate therewith. This is effected in the present instance by providing 25 the outer end portion of the adjusting shaft with a longitudinal spline-groove 76, in which a key 77 is received, the collar being provided with a complementary groove 78 for receiving said key.

30 The outer periphery of the collar 75 is provided with screw threads 79, and the inner periphery of the shell 69 is provided with internal threads 80 complementary to the threads 79. When the adjusting shaft 35 is rotated, the collar 75 rotates therewith, and, by means of its threaded connection with the inner periphery of the relatively stationary shell 69, the collar 75 is also moved endwise along the adjusting shaft.

40 A ring 83 is connected with said collar and moves endwise with the collar. This ring is shown received in an annular groove 84 in the collar. The collar is provided with a removable section 85, which forms one wall 45 of said groove, so that the ring may be received in the groove and the removable section be fixed in place, as by a screw 86.

Pins 87 extend radially from the ring, being shown as screws threaded in said ring 50 and extending through longitudinal slots 88 in the shell 69. A collar 89 is located about said shell and moves lengthwise along its outer periphery, and is connected with said pins so as to be moved lengthwise by 55 said pins, said pins being shown received through holes 90 in said collar.

A block 91, shown as a segment-block, is received about the outer periphery of the shell, and has connection, shown as a segmental tongue and groove connection 92, with the collar 89, so as to transmit the axial movements of the collar 89 to said block 91, and permit oscillatory movements of the housing 66 about the shell. The block is 65 held and moves lengthwise with relation to

said shell in a guide formed by the outer periphery of the shell and the inner periphery of the housing 66.

The housing 66 is normally stationary about the shell, but is permitted to have 70 slight oscillatory or rotative movement about the shell. The housing is a part of the means for feeding the work, and is normally held stationary with relation to the frame, but may have safety oscillatory movements 75 imparted thereto about the bearing-sleeve 56. When such oscillatory movements take place, the block 91 oscillates upon the collar 89 so as to maintain the stroke adjustment and its indication without change.

The housing is permitted to resiliently yield to undue strains upon the feeding mechanism, and to be held in normal position by a spring 95, the ends of which are received in thimbles 96, 97, provided with 85 enlargements forming annular shoulders 98, 99, the enlargements having endwise movements in a bore 100 of a lever 101, which is an element of the feeding means. Collars 102, 103, are fixed to the sides of said lever, as by screws 104, and form coacting shoulders for the shoulders 98, 99. A shank 105 is provided with heads 106, 107, arranged to abut the side walls 108, 109, of said housing. The housing is normally held in stationary 90 position during the feeding movements, but, upon undue strain, the housing is arranged to rock about the bearing sleeve 56, and to return to normal position upon release of 95 said undue strain.

The feeding movements are obtained by rotation of the block 48, which is an eccentric block, imparting rocking movements to a feeding lever pivoted on the housing, as more fully shown and described in Letters 100 Patent No. 1,637,969, A. M. Sosa, dated August 2, 1927, for feeding mechanism for metal working machinery. This patent also 105 more fully shows and describes the housing and spring construction herein above described.

The block 91 is provided with an indicating finger 111, which is shown fixed to said block by screws 112, the indicating finger being provided with a shank 113 received through a slot 114 extending lengthwise through the housing 66. The indicating finger is arranged to register with the markings of a scale 115, to indicate the adjustments of length of stroke of the tool-ram made by the adjusting shaft 42, when adjusting the distance of the crank-pin 31 from the axis of rotation of the bull-wheel. The indicating scale is shown on an indicating plate secured upon one of the walls of the slot 114 by screws 116. A cover plate 117 is secured, as by screws 118, to the other wall of said slot, and is received over the slot 114.

A socket-piece 121 is secured to the outer 115 end of the shell 69, and forms an extension 120

of the same. The socket-piece is provided with a rabbet 122, in which the outer end of the shell is received, a shoulder 123 at the end of said rabbet mating with the outer 5 end of the shell. Screws 124 secure said socket-piece and the outer end of the shell together.

A plunger 125 is received about the outer 10 end of the adjusting shaft 42, and is rotatively held thereto, as by means of a key 126 received in a key-way 127 in said plunger and in the spline-groove 76. A spring 128 is received about the hub 129 of said plunger and is located between the flange 130 of said 15 plunger and the bottom wall 131 of the socket 132 in the socket-piece, for normally urging the plunger outwardly. The hub of the plunger and the spring are arranged to be received in said socket to desirable extent.

20 A cap 135 is received crosswise of the outer end of the socket-piece, being secured thereto by screws 136, and forms an inwardly extending flange for the outer end of the socket-piece. A clutch 137, shown as 25 a tooth-clutch, has its teeth located respectively on the plunger and the cap, so as to hold said plunger in angular position with relation to the socket-piece when the clutch is engaged, for fixing the shell 69 and the 30 adjusting shaft 42 in rotative relation when said clutch is engaged, and permitting rotation of the adjusting shaft 42 with relation to the shell when said clutch is disengaged.

The teeth of the clutch are preferably fine 35 teeth so that upon minute rotative adjustments of the adjusting shaft 42 with relation to the shell, and consequently with relation to the bull-wheel, being made, the teeth of the clutch will be reengaged in new relations 40 after such adjustments are completed.

The outer end of the shaft is formed to receive a suitable wrench, and the wrench is so formed and it and the clutch collar or plunger are so related that when the wrench 45 is connected with the adjusting shaft 42 for making an adjustment, it also releases the clutch 137 for permitting the desired relative rotation between the operating shaft and the shell, and consequently between the 50 operating shaft and the bull-wheel.

Thus a wrench 141 is provided with a handle 142 and with a socket-piece 143, arranged to be received about the outer end of the adjusting shaft to sufficient extent to 55 push the plunger 125 inwardly and thereby disengage the clutch, the wrench being received through a hole 144 in the cap 135. The outer end of the adjusting shaft is shown as square ended, the inner end of the 60 socket of the wrench being complementally formed to coact therewith for turning the adjusting shaft.

I do not herein specifically claim the 65 clutch mechanism, having shown, described and claimed the same in a copending appli-

cation for improvements in metal working machinery, filed December 20th, 1926, as Serial No. 155,965.

In operation, the bull-wheel rotates and carries the crank-pin with it in its rotations, 70 for rocking the rocker-arm, and consequently reciprocating the tool-ram. The length of stroke of the tool-ram is determined by the distance of the crank-pin from the axis of rotation of the bull-wheel. During rotation of the bull-wheel, the hub 45 thereof and the bushing 46, as well as the shell 69, the socket-piece 121 thereof, the clutch 137, the plunger 125, the adjusting shaft 42, and the threaded collar 75, rotate 75 with the bull-wheel, the ring 83 remaining non-rotative in its annular groove in the threaded collar.

When it is desired to adjust the stroke of 80 the tool-ram, which may be effected while the tool-ram is reciprocating or at rest, the wrench is pushed inwardly about the outer end of the adjusting shaft for pushing the plunger 125 and disengaging the clutch 137, and engaging the complemental faces of the 85 wrench and adjusting shaft, whereupon rotation is imparted to the adjusting shaft 42 by means of the wrench, in either direction, 90 relatively to the shell 69, for causing either a longer or a shorter stroke of the tool-ram. 95

Such rotation of the adjusting shaft 42 rotates the threaded collar 75 with relation to the shell, thereby effecting axial movement of the threaded collar in desired direction along the adjusting shaft 42, by 100 reason of the connection of the threaded outer periphery of said collar with the threaded inner periphery of the shell, the extent of such adjustment being indicated simultaneously by movement of the indicating 105 finger 111 lengthwise of the scale 115, the adjustment being continued until the desired length of stroke of the tool-ram is indicated by the position of the indicating finger on the scale, whereupon the wrench is withdrawn, and the clutch is automatically reengaged in the new relation between the adjusting shaft, the crank pin and the bull-wheel. 110

Having thus fully described my invention, 115 what I claim as new, and desire to secure by Letters Patent, is:

1. In mechanism of the character described, the combination with a power transmitting crank member comprising a crank 120 adjustable toward and from its axis of rotation, of an adjusting shaft, an internally threaded shell surrounding said shaft, said shaft rotatable with relation to said shell for adjusting said crank, an internally 125 threaded shell surrounding said shaft, an externally threaded part complemental to the internal threads of said shell, the internal threads of said shell and the external threads of said part spaced from said shaft 130

- by the body of said part, said part having connection with said shaft whereby said part is rotated with said shaft by said shaft and is permitted to be fed lengthwise along 5 said shaft by said threads upon rotation of said shaft, said shaft, part and shell concentrically arranged, and an indicating element having operative connection with said part for receiving indicating movements.
- 10 2. In mechanism of the character described, the combination with a rotative power transmitting member, and a power transmitting crank on said member adjustable toward and from the axis of rotation 15 of said member, of an adjusting shaft for said crank whose axis of rotation is coincident with said first-named axis, an internally threaded shell about said shaft spaced from said shaft and arranged to rotate with 20 said member, an externally threaded part complementary to said internally threaded shell, said externally threaded part having connection with said shaft, said connection causing said externally threaded part to 25 rotate with said shaft, said externally threaded part shiftable by the threads of said shell and said part along said shaft, the internal threads of said shell and the external threads of said part spaced from said 30 shaft by the body of said part, a housing about said shell, and a complemental scale and pointer forming a pair of indicating elements, one of which is located on said housing and the other of which has operating 35 connection with said part.
3. In mechanism of the character described, the combination with a rotative power transmitting member, a power transmitting crank on said member adjustable 40 toward and from the axis of rotation of said member, an adjusting shaft whose axis of rotation is coincident with said first-named axis, an internally threaded shell arranged to rotate with said member, an externally threaded part complementary to said internally threaded shell, the internal threads of said shell and the external threads of said part spaced from said shaft by the body of said part, said shaft, shell 45 and part concentrically arranged, connecting means connecting said shaft and said part causing said part to rotate with said shaft and to permit shifting of said part in axial directions along said shaft, an indicating scale, a pointer therefor having operative connection with said part, a relatively stationary support, and a guide on said support parallel with said axis of rotation for guiding said pointer.
- 50 4. In mechanism of the character described, the combination with a tool-ram, a rotative power transmitting member therefor, a power transmitting crank thereon adjustable toward and from the axis of rotation of said member, an adjusting shaft 55 for adjusting said crank, an internally threaded shell arranged to rotate with said member, a housing thereabout, said internally threaded shell and said housing provided with parallel slots extending lengthwise of said shell and said housing, an externally threaded part complementary to said internally threaded shell, the internal threads of said shell and the external threads of said part spaced from said shaft by the body of said part, said housing, shaft, shell and part concentrically arranged, connecting means connecting said part and said shaft to cause said part to 60 rotate with said shaft and to permit shifting of said part in axial directions along said shaft, a collar movable axially with said part, said part having rotative connection with said collar, a collar about said shell, connecting means between said collars in said slot in said shell, said connecting means guided by the walls of said slot, said housing provided with an indicating scale and a finger having attachment with said second-named collar and extending through said slot in said housing for coactive relation with said scale and indicating on said scale the reciprocating movements of said tool-ram.
5. In mechanism of the character described, the combination with a power transmitting crank member comprising a crank adjustable toward and from its axis of rotation, of a normally stationary housing capable of oscillating, an adjusting shaft for said crank therein, a pair of complementary indicating elements, one of said elements located on said housing, and feeding means having operative connection with said shaft for feeding the other of said elements relative to said one of said elements, said feeding means received through the wall of said housing for similar movements of said other of said elements relative to said one of said elements throughout rest position and oscillating movements of said housing.
6. In mechanism of the character described, the combination with a reciprocating tool-ram and a power transmitting crank member for operating said tool-ram, said crank member comprising a crank adjustable toward and from its axis of rotation, of a normally stationary housing capable of oscillating, an adjusting shaft for said crank therein, a pair of complementary indicating elements, one of said elements located on said housing, a controlled member, and means for feeding said controlled member lengthwise of said shaft by rotation of said shaft, said controlled member having operative connection with the other of said elements, and said other of said elements received through said housing for movement relative to said one of said elements.

ments whereby to indicate the adjustments of stroke of said tool-ram throughout rest position and oscillating movements of said housing.

- 5 7. In mechanism of the character described, the combination with a power transmitting crank member comprising a crank adjustable toward and from its axis of rotation, of an internally threaded shell, an adjusting shaft in said shell rotatable with relation thereto for adjusting said crank, an externally threaded part complementary to the internal threads of said shell and having connection with said shaft.
- 10 10 an adjusting shaft in said shell rotatable with relation thereto for adjusting said crank, an externally threaded part complementary to the internal threads of said shell and having connection with said shaft.
- 15 15 whereby said part is fed lengthwise along said shaft by said threads upon rotation of said shaft, the internal threads of said shell and the external threads of said part spaced from said shaft by the body of said part.
- 20 20 said shaft, part and shell concentrically arranged, an indicating element having operative connection with said part, a clutch between said shell and said shaft comprising a clutch collar arranged to rotate with said
- 25 25 shaft and movable axially therewith by a turning tool when rotating said shaft to shift said indicating element, and resilient means returning said clutch collar into clutch relation for fixing said indicating element.

- 30 8. In mechanism of the character de-

scribed, the combination with a power transmitting crank member comprising a crank adjustable toward and from its axis of rotation, of an internally threaded shell, an adjusting shaft in said shell rotatable with relation thereto for adjusting said crank, an externally threaded part complementary to the internal threads of said shell and having connection with said shaft whereby said part is rotated by said shaft and is fed lengthwise along said shaft by said threads upon rotation of said shaft, the internal threads of said shell and the external threads of said part spaced from said shaft by the body of said part, said connection causing said shaft and said part to rotate together, said shaft, part and shell concentrically arranged, an indicating element having operative connection with said part for receiving indicating movements, a clutch between said shaft and said shell comprising a movable member arranged for release relation by a turning tool when received about said shaft for turning said shaft, and means automatically returning said clutch member into engaged relation upon removal of said turning tool.

In testimony whereof, I have hereunto signed my name.

HANS BAERBALCK.

CERTIFICATE OF CORRECTION.

Patent No. 1,700,966.

Granted February 5, 1929, to

HANS BAERBALCK.

It is hereby certified that error appears in the printed specification of the above numbered patent requiring correction as follows: Page 2, lines 118 and 119, for the word "morkings" read "markings"; page 3, lines 125 and 126, claim 1, strike out the words and comma "an internally threaded shell surrounding said shaft,"; and that the said Letters Patent should be read with these corrections therein that the same may conform to the record of the case in the Patent Office.

Signed and sealed this 26th day of February, A. D. 1929.

M. J. Moore,
Acting Commissioner of Patents.

(Seal)
